LOOSE COILING INSTALLATION

Douglas H. Keen and Gale E. Paxton, Burlington, Ontario, Canada, assignors to Swindell-Dressler Corporation, Pittsburgh, Pa., a corporation of Pennsylvania
Filed Aug. 16, 1960, Ser. No. 49,995
18 Claims. (Cl. 242—78.1)

This invention relates to apparatus and to a method for converting tightly wound coils of stiff flat strip material, such as cold rolled steel, plastic and paper into loosely wound coils with a controlled gap spacing between each lap, and for reconverting the loose coils back into tight coils.

The apparatus and method are of special use in the steel industry where it is practice to anneal and "gas alloy" cold rolled steel in the loosely-coiled form. The general process of reducing the carbon content in cold rolled steel as it is annealed by "gas alloying," that is, passing a controlled atmosphere of gas over the surface of the steel, is well known, and multiple mandrel apparatus and methods have been developed for converting coils of steel from a tightly wound condition to a loosely wound condition that will permit the alloying gases to pass freely over the surfaces of the steel. This invention relates to an improved apparatus and method for converting the coils from the tightly wound condition to the loosely wound condition and vice versa.

Generally speaking, apparatus according to this invention for converting a coil of strip material from a tight wind to a loose wind, comprises a substantially vertical rotatable mounted mandrel adapted to grip the inside end of a coil of strip material and a rotatably mounted support table, the support surface of which is substantially in a horizontal plane. A presser roll is provided that is adapted to press against the outside of the tight roll. The mandrel and presser roll are rotated to reel the strip from a tight roll on the mandrel to a loose roll on the table. At the same time, the table is rotated at a speed to take up and loosely coil the strip material inwardly of a point where it is secured thereto. The invention will be clearly understood after reference to the following detailed specification read in conjunction with the drawings.

In the drawings,

FIGURE 1 is a general view of apparatus according to this invention, partly broken away to illustrate principal components, and

FIGURE 2 is a plan view showing how the apparatus converts a tightly wound coil to a loosely wound coil.

In the drawings there is shown a mandrel, generally indicated by the numeral 10 rotatably mounted on the free end of a piston 12 that extends from a cylinder 14. The mandrel is formed with an expandable end 16 that is adapted, in use, to enter into the opening at the inside diameter of a coil of strip steel and be expanded to securely mount the coil thereon with the inside free end secured thereto. Expanding coil engaging mandrels for strip steel are well-known in the art and detail is not shown in this specification.

The mandrel 10 is rotated in use within its mounting by means of the motor 18 through the gear box 20. The shaft of the mandrel is splined where it engages the drive gear 22 to permit the mandrel to slide vertically of its longitudinal axis as the piston 12 is moved inwardly and outwardly of its double acting cylinder 14 under the control of hydraulic fluid fed thereto through the lines 22. The mandrel 10 has been illustrated in an extended position in FIGURE 1 with the coil engaging end 16 thereof extending above the rotatably mounted support table 26. The mandrel can be dropped to cause the coil engaging end 16 thereof to disappear beneath the support

2

surface of the table 26 by causing the piston 12 to drop within its cylinder 14. As this occurs the splined shaft of the mandrel slides through the drive gear 22 of the gear box 20.

5 The table 26 is mounted for rotation on the circular track 40 on the base 41 of the machine. It will be noted that the table has spaced apart wheels 42 on the underside thereof, that ride on the circular track 40, which is concentric with the centre of rotation of the spindle 10.

10 A motor 46 is adapted to turn the table 26 about the track 42 through the gear box 48, the pinion 50 of which engages with a circular track 52 on the underside of the table 26.

A clamping bar 54 is provided on an outside vertically extending wall of the table 26 for the purpose of clamping the outer free end of a coil 56 of strip material with respect to the table.

15 A small rubber-covered presser roll 60 rotatably mounted within a bracket or crank assembly 62, is 20 adapted in use to press against the outer lap of a tightly wound coil, on the mandrel. In the embodiment of the invention illustrated, it is driven within its rotatable mounting by means of a motor 64 through a gear box 66.

25 Bracket 62, upon which the presser roll 60 is mounted, is rigidly connected to the shaft 68. Shaft 68 in turn is slidably mounted in a vertical direction and rotatable within the lugs 70 on rigid post 72. Shaft 68 pivotally joined with piston rod 74 of cylinder 76 at its lower end 30 so that it can turn about its own longitudinal axis with respect thereto. Piston rod 74 has a square cross section and is slidably longitudinally of itself within its support lug 78. It can not, however, rotate within its support lug.

35 Another arm of bracket 62 has a vertically extending post 80 that slidably connects with the free end of a piston 82. The other end of piston 82 is pivotally mounted to the rigid post 84.

In use as will be referred to later, hydraulic piston 32 40 is operated to turn the crank assembly 62 in the direction of the arrow to cause the presser roll 60 to overlie the support surface of the take up table 26. Piston 74 is then dropped in its cylinder 76 to permit the crank assembly 62 to fall and lower the presser roll 60 to the height of a coil 56 of strip material overlying the table. The cylinder 82 is then extended to urge the presser roll 60 against the outside of the strip with considerable force to keep the coil on the mandrel tightly wound.

The invention can be used for the converting of strip 50 steel from tightly wound coils to loosely wound coils and vice versa. These coils, in the case of cold rolled steel when tightly coiled, have an inside diameter of between 20" and 24" and an outside diameter of up to 72". The width of the strip material varies. A common 55 width is 48 inches. However, the material is manufactured in widths up to 72 inches. It is common practice to take a tightly wound coil having an inside diameter of 20 inches and an outside of 72 inches and convert it to a loosely wound coil having an inside diameter of about 36 inches and an outside diameter of 114 inches. This gives gap thickness between adjacent laps of the coil 60 of about one and one-half times the strip thickness.

The manner of using the apparatus described is as follows. With the presser roll 60 in the inoperative position illustrated in FIGURE 1 of the drawings, and the upper portion 16 of the mandrel 10 retracted to a position below the polished bearing surface of the take up table 26, a tightly wound coil of strip steel is centred over the table with the centre opening thereof aligned with the central opening in the take up table. The strip steel is handled by means of a crane having a magnetic holding device (not shown and not part of this invention).

The mandrel 10 is then raised by operation of cylinder 14 to partially extend the end 16 thereof into the centre opening of a coil of strip material 56. The coil is then lowered onto the bearing surface of the take up table 26 and the mandrel 10 is extended into the centre of the opening of the coil to within about one-eighth of an inch of its full raised position. The inside end of the strip of coil material is then fixed to the mandrel and the coil engaging end 16 of the mandrel is expanded to tightly engage with the central opening of the tight coil of strip material. The mandrel is then raised to its full extent to lift some of the weight of the tightly wound coil from the table.

The outside end of the coil of steel is then unravelled and clamped to the outer peripheral wall of the take up table 26 as at 54.

The support crank 62 is then raised to clear the wall of the table by operation of cylinder 74 swung in the direction of the arrow of FIGURE 1 to overlie the table by operation of cylinder 82, dropped over the table 26 by operation of cylinder 74 and swung to press the presser roll 60 into pressing contact with the outer lap of the tight coil. Alternatively, the presser roll could be caused to engage with the tightly coiled roll 56 of strip material before the outer end thereof is clamped as at 54.

The take up table 26, the mandrel 10, and the presser roll 60 are then simultaneously rotated by means of their respective drive means 46, 18 and 64 respectively to unreel the strip material from the tightly wound coil.

As the strip material is unreeled from the point where the presser roll 60 engages with the outside diameter of the coil 56, the take up table 26 rotates to take up the unwound strip and support it on its side edge in a loosely wound coil having an outside diameter equal to the diameter of the table, and with a space between adjacent laps. The process continues until all of the tightly wound coil is fed to the loosely wound coil.

It will be apparent that the relative speeds of the mandrel, presser roll, and support table will constantly change because the point on the table where a particular strip section is fed as it is unreeled and where it is intended that it should be supported in spiral formation must travel at the same speed as the unreeled strip at the time of its arrival at the point where it is to be supported so that there is no relative movement between the two and the table can take up the strip in spiral form. If the rate of unreeling is constant and a constant gap between laps on the loose coil is desired the rate of turning of the outer table will have to constantly increase as strip material is unreeled to achieve this. The relative rates of rotation of the mandrel and presser roll will also change as the tight coil is unwound. FIGURE 2 is a plan view of the table 26 showing a tightly wound coil 56 in the process of being reeled out onto the take up table 26 upon which it is supported to its side edges in a loosely wound coil having a gap 90 between adjacent laps. The steel is reeled out over the table as at 92 and continues to move with respect to the table until it overlies a take up point thereon that is traveling at the same speed that it is travelling. At this point, it continues to travel with the table and does not move with respect thereto. As indicated above the rate of rotation of the table is adjusted such that the table takes up the unreeled strip in a spiral formation. This speed of the table is varied such that the said take up point travels spirally inwardly from where the free end of the strip is secured to the table as at 54 along a spiral path upon which the steel is supported with spaced apart gaps 90 as indicated. The continuously necessary changes in rotational speed of the table can be controlled conveniently by means of a computer. Necessary changes in the speeds of the mandrel and presser roll can also be controlled by means of a computer.

To increase the width of the gap 90 one would increase the speed of rotation of the table and keep the speed of unreeling constant. It will also be apparent that

gap width can be controlled by unreeling speed or by a combination of unreeling speed and table speed.

After the coil has been fully unreeled from the tight roll 56 and is in the form of a loose coil with gaps 90 between each lap, the inside end thereof is released from the mandrel. The mandrel is dropped below the table and the loose coil is lifted by means of a crane into a heat treating furnace. After heat treating the loose coil is again centred on the table with the mandrel in the lower position. The mandrel is then raised as before and the inside end of the loose coil is inserted into the gripper of the mandrel and the mandrel is expanded. The mandrel presser roll and table are again rotated in synchronization to uniformly rewind the loose coil onto the outside of the mandrel. The presser roll being used as a drag on the outer lap of the tight coil to maintain tension as the coil is tightly wound on the mandrel. When the full coil has been tightened the mandrel is collapsed and retracted into the base and the tightened coil is removed by means of the magnetic crane.

Modifications in the invention will, of course, be apparent to those skilled in the art. It may, for example, be desirable to permit the table to idle in the rewind application rather than drive it in synchronization; or in the earlier operation of unreeling of the tightly wound coil, it may be desirable to let the mandrel idle. Further, it may well be possible to practice the invention without the presser roll provided that the stiffness of the material is sufficient to carry it across the takeup table to the point where it is loosely coiled thereon in the unwinding operation. In some instances, depending on the material being handled, it may also be possible to rewind the material into a tight coil without the presser roll. These things and others are variable within the scope of the invention.

What we claim as our invention is:

1. Apparatus for converting a coil of strip material from a tight wind to a loose wind with a gap between adjacent laps comprising a rotatably mounted mandrel adapted to grip the inside end of a coil of strip material, a table having a support surface adapted to support a loosely wound coil of strip material, means on said table for securing the free end of a coil of strip material, its longitudinal axis substantially at right angles to the support surface of said table and at the centre thereof, a presser roll, means for rotatably mounting said presser roll for rotation with respect to strip material reeled from and onto said mandrel respectively, means for urging said presser roll towards said mandrel to keep a coil between said roll and said spindle tight, separate means for rotating said mandrel and presser roll to reel a coil of strip material from said mandrel out onto said table and in from said table onto said mandrel, and means for rotating said table to loosely coil strip material thereon as it is reeled from said mandrel and to feed strip towards said mandrel as it is reeled onto said mandrel.

2. Apparatus as claimed in claim 1 in which said separate means for rotating said mandrel and presser roll comprises drive means for rotating said mandrel and a drive means for rotating said presser roll.

3. Apparatus as claimed in claim 1 in which said table has an opening adjacent to its centre, and having means for moving said mandrel and table with respect to each other whereby said mandrel can be dropped with respect to said table.

4. Apparatus as claimed in claim 1 in which said table has an opening adjacent to its centre, and having means for moving said mandrel and table with respect to each other whereby said mandrel can be dropped with respect to said table, in which said separate means for rotating said mandrel and presser roll comprises drive means for rotating said mandrel and a drive means for rotating said presser rolls.

5. Apparatus as claimed in claim 1 in which said

table is formed with an opening adjacent its centre, and in which there are means for moving said mandrel longitudinally of the table through said opening in said table whereby said mandrel can be dropped beneath the surface of said table.

6. Method of forming a tight coil of strip material to a loose coil strip material comprising the steps of supporting the tight coil for rotation with its rotational axis substantially vertical, fixing the outside end of the tight coil on a rotatable support surface outwardly of the tight coil a distance equal to the outside diameter of the loose coil to be wound, exerting a pressure against the outside of the tight coil where the strip material extends therefrom, turning said tight coil about its axis to unreel it from the point where pressure is exerted thereagainst, and supporting the strip material on a side edge thereof as it is unreeled onto said support surface while continuously turning the support surface to loosely coil the material inwardly of the place where it is fixed thereto as aforesaid.

7. A method as claimed in claim 6 in which said support surface is turned at a rate from the beginning of the unreeling of the tight coil such that there is a point thereon that travels at the same rate of speed as the rate of speed of unreeling of strip from said tight coil said point moving spirally inwardly from where said strip is attached to said surface towards the centre of rotation as unreeling of the tight coil progresses, the strip being loosely coiled as aforesaid on the locus of said point.

8. A method as claimed in claim 7 in which said support surface and said coil are turned about a common axis of rotation.

9. A method as claimed in claim 6 in which said support surface and said coil are turned about a common axis of rotation.

10. A method of forming a loose coil of strip material into a tight coil comprising the steps of supporting the loose coil on a side edge of the strip on a rotatable support surface, securing the inside end thereof to a mandrel at the centre of the loose coil rotating the mandrel and support surface at relatively differing coordinated speeds to wind the strip onto the mandrel while maintaining a drag on the strip wound onto the mandrel by exerting a force against the outside lap of strip on the mandrel.

11. Apparatus for converting a coil of strip material from a tight wind to a loose wind with a gap between adjacent laps comprising a rotatably mounted mandrel adapted to grip the inside end of a coil of strip material, a table having a support surface adapted to support a loosely wound coil of strip material, means on said table for securing the free end of a coil of strip material, its longitudinal axis substantially at right angles to the support surface of said table and at the centre thereof, means for rotating said mandrel to reel a coil of strip material from said mandrel out onto said table and in from said

50

55

table onto said mandrel, and means for rotating said table to loosely coil strip material thereon as it is reeled from said mandrel and to feed strip towards said mandrel as it is reeled onto said mandrel.

5 12. Apparatus as claimed in claim 11 in which said table has an opening adjacent to its centre, and having means for moving said mandrel and table with respect to each other whereby said mandrel can be dropped with respect to said table.

10 13. Apparatus as claimed in claim 11 in which said table is formed with an opening adjacent its centre, and in which there are means for moving said mandrel longitudinally of the table through said opening in said table whereby said mandrel can be dropped beneath the surface of said table.

15 14. Method of forming a tight coil of strip material to a loose coil strip material comprising the steps of supporting the tight coil for rotation with its rotational axis substantially vertical, fixing the outside end of the tight coil on a rotatable support surface outwardly of the tight

20 coil a distance equal to the outside diameter of the loose coil to be wound, turning said tight coil about its axis to unreel it, and supporting the strip material on a side edge thereof as it is unreeled onto said support surface while

25 continuously turning the support surface to loosely coil the material inwardly of the place where it is fixed thereto as aforesaid.

15 15. A method as claimed in claim 14 in which said support surface is turned at a rate from the beginning of

30 the unreeling of the tight coil such that there is a point thereon that travels at the same rate of speed as the rate of speed of unwinding of strip from said tight coil said point moving spirally inwardly from where said strip is attached to said surface towards the centre of rotation as unwinding of the tight coil progresses, the strip being loosely coiled as aforesaid on the locus of said point.

16. A method as claimed in claim 15 in which said support surface and said coil are turned about a common axis of rotation.

40 17. A method as claimed in claim 14 in which said support surface and said coil are turned about a common axis of rotation.

18. A method of forming a loose coil of strip material into a tight coil comprising the steps of supporting the loose coil on a side edge of the strip on a rotatable support surface, securing the inside end thereof to a mandrel at the centre of the loose coil, correspondingly and respectively rotating the mandrel and support surface to wind the strip onto the mandrel.
